HUSKING MECHANISM

Norman F. Andrews, Moline, Ill., assignor to Deere & Company, Moline, Ill., a corporation of Illinois

Application January 31, 1944, Serial No. 520,566

6 Claims. (Cl. 130—5)

The present invention relates generally to husking mechanism and has for its principal object the provision of a novel and improved means for mounting a pair of husking rolls.

As is well-known to those skilled in the art, a husking device comprises a pair of rolls disposed closely adjacent one another and rotated in relatively opposite directions, whereby the rolls grasp the husks and silks of the ears of corn which are placed upon the pair of adjacent rolls, passing the husks and silks between the rolls and discharging them to a suitable conveyor or other means of disposal at the opposite side of the pair of rolls. Occasionally, a piece of cornstalk, corn cob, or a small undeveloped ear of corn is grasped between the rolls, and would cause damage to the rolls and to the driving mechanism therefor, if it were not for the fact that the rolls are yieldably mounted so that they can spread apart to pass the object between the rolls. Thus, it is conventional to provide a resilient mounting for the bearings at the opposite ends of the rolls, so that either end of the pair of rolls may be spread apart. Obviously, this necessitates some complication in the drive connections to the husking rolls. Furthermore, it is difficult to enclose the drive gears in a gear case filled with lubricant in the conventional husking mechanism, since the shiftable bearings introduce the problem of maintaining lubricant-tight seals in the wall of the gear box.

It is a specific object of my invention, therefore, to provide a husking roll arrangement and mounting which permits a simple, positive drive connection. Still another object has to do with the provision of a husking roll arrangement in which the bearings at the drive end of the husking rolls are not shiftable, thereby permitting the drive gears to be enclosed in a lubricant-tight housing or box without any complicated lubricant sealing devices, while at the same time, retaining the advantages of having the rolls shiftably mounted so that they may spread apart at either end to pass pieces of cornstalks, cobs, and small undeveloped ears, and the like.

These and other objects and advantages of my invention will become apparent to those skilled in the art after a consideration of the following description of an embodiment shown in the accompanying drawing, in which

Figure 1 is a plan view of a husking box embodying the principles of my invention.

Figure 2 is a sectional elevational view taken along a line 2—2 in Figure 1.

Figure 3 is a sectional elevational view taken along a line 3—3 in Figure 1.

Figure 4 is a sectional elevational view taken along a line 4—4 in Figure 1.

Referring now to the drawing, the husking mechanism comprises a husking box 5 comprising a pair of long sheet metal side walls 6, interconnected at one end by a vertical end wall 7 having flanges 8 extending vertically along the side edges and suitably connected to the ends of the side walls 6, as by rivets or welding. The opposite ends of the side walls 6 are connected to the opposite end walls of a gear box or transmission housing 9, which is preferably totally enclosed and filled or partially filled with lubricant. Between the gear box 9 and the end wall 7, the husking box 5 is open at the top and bottom to permit ears of corn to be fed into the top of the box and to permit silks, husks, leaves and other trash to be discharged from the bottom of the box in a manner well-known to those skilled in the art. The feeding and conveying means above and below the husking box are not shown nor are they described herein, since they form no part of the present invention.

A pair of husking rolls, indicated generally by reference numerals 12 and 13, extend longitudinally through the husking box between the transmission housing 9 and the end wall 7. Each of the husking rolls 12, 13 comprises a cylindrical roll member 14 having a hollow interior 15, and a shaft 16 of polygonal cross section, preferably square, extending longitudinally or axially through the hollow interior 15 of the member 14. One end of each of the shafts 16 extends through a suitable aperture in the inner wall 17 of the gear box 9 and the other ends of the shafts extends through suitable apertures in the end wall 7 of the husking box 5.

The drive ends of the shafts 16 are mounted in a pair of bearings 18, which are mounted within the apertures 19 in the wall 17 on relatively fixed centers. The bearings 18 are provided with flanges 20, which are secured to the wall 17 by suitable bolts 21 and are provided with sealing gaskets 22 to prevent any leakage of lubricant through the apertures 19. The ends of the square shafts 16 are, of course, made cylindrical to permit them to turn in the bearings 18. A bevel gear 23 is fixed to the end of one of the shafts 16 by means of a suitable pin 24, and is disposed in mesh with a beveled drive gear 25, which is fixed on a drive shaft 26, disposed transversely of the gear box 9 and supported in journal bearings 27 in opposite walls of the gear box 9, respectively.

A drive sprocket 28 is fixed to one end of the drive shaft 26 outside the gear box 9.

The shaft 16 which is provided with the bevel gear 23, is journaled in a bearing 30 at its opposite end, the bearing 30 being mounted within a circular aperture 31 in the end wall 7. The bearing 30 fits snugly within the aperture 31 and is not shiftable in a radial direction, therefore it will be seen that the shaft carrying the bevel drive gear 23 is journaled on a fixed axis relative to the husking box. The bearing 30 is provided with a securing flange 32 which is secured to the outer side of the end wall 7 by means of a bolt 33 engaged between a pair of lugs 34 on the flange 32. Power may be taken from the end of this shaft by means of a suitable gear or sprocket 35 fixed to the extremity of the shaft by means of a pin 36.

The shaft 16 of the other roll 13 is supported in a bearing 40 disposed within an aperture 41 in the end wall 7. This bearing 40 is provided with a flange 42 on the outer side of the wall 7 and is pivotally connected to the latter by means of a pivot bolt 43 passing through a suitable aperture in an extended portion 44 of the flange 42 and through an aligned aperture in the end wall 7. The bearing aperture 41 is arcuate in shape, so that the bearing can be swung laterally about the axis of the pivot bolt 43 and will slide through the arcuate slot 41 away from, and toward the bearing 30. The bearing 40 is urged toward the bearing 30 by means of a compression coil spring 48, which encircles a bolt 49 extending transversely through a lug 50 on the top side of the bearing 40, over the bearing 30, and through an aperture in the flange 8 of the end wall 7. The spring 48 is disposed on the end of the bolt 49 between the side wall 6 and a nut 51, threaded on the end of the bolt 49. The pressure of the spring 48 can be adjusted by turning the nut 51 on the bolt 49 to adjust the amount of force which urges the roll 13 toward the roll 12 at this end of the pair of rolls. The bearing 18 at the opposite end of the shaft 16 from the bearing 40 is provided with sufficient looseness to accommodate the lateral shifting movement of the bearing 40 within the arcuate aperture 41, about the axis of the pivot bolt 43.

Each of the cylindrical roll members 14 is provided with a hub portion 55 adjacent the opposite ends of the members 14 from the gear box 9. These hub portions 55 are provided with square apertures 56 adapted to receive the square shafts 16 and prevent relative rotation between the roll members 14 and the shafts 16 so that the roll members may be driven through the hubs 55 by power transmitted through the shafts 16. The shafts 16 fit within the apertures 56 sufficiently loosely, however, to permit the roll members 14 to swing relative to the shafts 16 about generally radially disposed axes passing through the hubs 55. That is to say, the hub portions 55 fit sufficiently closely on the shafts 16 to prevent any appreciable amount of lateral play between the hub portions 55 and the shafts 16, but permit the opposite ends of the roll members 14 to have an appreciable amount of lateral play relative to the shafts 16 within the rolls.

The roll members 14 are normally retained in coaxial relation with the shafts 16 by resilient means in the form of coil springs 58 disposed on radially extending axes and bearing between the shaft 16 and the interior wall of the roll members 14. The coil springs 58 are stressed in compression and oppose each other in balanced relation

to center the shaft within the roll member. As best shown in Figure 4, each of the coil springs 58 bears against one of the flat sides of the square shafts 16 and is seated within a drilled hole 59 in the wall of the cylindrical roll member 14. Each of the holes 59 is threaded to receive a plug 60, against which the coil spring 58 reacts. Each of the plugs 60 is provided with a slot 61 adapted to receive a screw driver during installation or removal of the plug.

Preferably, there are four springs 58, spaced 90-degrees apart, although it is possible to use three, five, or more spaced equally in order to balance the opposing forces of the springs. It will be noted that the axes of the several springs are all disposed in one transverse plane, although it is not absolutely essential that all springs be in exactly the same plane, but may be slightly offset if so desired.

Although the husking rolls are shown with smooth cylindrical surfaces, it is understood that any of the conventional surfaces now applied to husking rolls can be used with this type of husking mechanism.

Power is applied through any suitable power transmitting device to the sprocket 28 on the drive shaft 26, and the drive power is transmitted through the intermeshing beveled gears 23, 25 to the associated square shaft 16. The other roll shaft 16 is driven through a pair of intermeshing spur gears 62, 63 rigidly mounted on the two shafts 16, respectively, adjacent the shaft bearings 18 immediately outside the wall 17 of the gear box 9. However, if desired, the gears 62, 63 can be mounted inside the gear box 9 if the latter is made slightly larger, as will be apparent to those skilled in the art. The power is applied in the direction which will cause the rolls to turn in relatively opposite directions in such a manner as to cause the adjacent surfaces of the rolls to travel downwardly, in order to grasp therebetween any leaves, husks or silks that are adhering to the ears of corn which are brought into proximity to the upper sides of the rolls. In case that a cob or stalk be grasped between the rolls near the drive end of the shafts, the cylindrical roll members 14 spread apart to pass the cobs therebetween, by virtue of the coil springs 58 yielding and permitting the roll members 14 to swing apart angularly relative to the drive shafts 16. In this case, there is no lateral shifting movement of the drive shafts, inasmuch as the bearings 18 in the gear case 9 are on relatively fixed axes. Hence, it is apparent that the yielding movement of the roll members 14 in this case, does not interfere with the drive mechanism, since there is no yielding movement of the shafts 16 and thus no relative shifting movement of either the bevel gears 23, 25 or the spur gears 62, 63.

In case a cob or stalk is caught between the opposite ends of the roll members near the hubs 55, there is substantially no lateral movement of the roll members 14 relative to the shafts 16, but the rolls spread apart by virtue of the bearing 40 pivoting about the pivot bolt 43 and spreading apart from the other roll member against the action of the compression spring 48. As soon as the object has passed through the rolls, the spring 48 returns the roll 13 to its normal position in substantial engagement with the surface of the roll 12. This angular shifting movement of the shaft 16 of the roll 13 has a negligible effect on the meshing of the gears 62, 63 at the other end of the rolls.

When an object is passed between the rolls near the center of the rolls, the yielding movement is a combination of the two yielding movements described above.

I claim:

1. In combination, a pair of roll shafts, a pair of bearings disposed on relatively fixed centers for supporting adjacent ends of said shafts, respectively, power transmitting means connected with said shafts near said bearings, for driving said shafts in relatively opposite directions, a second pair of bearings for supporting the opposite ends of said shafts, respectively, supporting means for said second pair of bearings providing for relative movement toward and away from each other, resilient means for urging said bearings toward each other, a pair of hollow rolls mounted on said shafts, respectively, between the bearings, means securing the ends of said rolls adjacent said second pair of bearings to said shafts but permitting the rolls to shift angularly about axes perpendicular to said shafts adjacent the last mentioned ends, thereby permitting the ends of said rolls adjacent said fixed bearings to move apart, and resilient means disposed between said shafts and their respective rolls for yieldingly retaining said rolls in coaxial relation to said shafts, respectively.

2. In a husking mechanism, the combination of a gear box, a pair of husking roll shafts extending through one wall of said box in spaced relation, a pair of bearings mounted in said wall on relatively fixed centers for supporting said shafts, respectively, power transmitting means disposed within said box connected to drive said shafts in relatively opposite directions, a second pair of bearings for supporting the opposite ends of said shafts, respectively, supporting means for said second pair of bearings providing for relative movement toward and away from each other, resilient means for urging said bearings toward each other, a pair of hollow husking rolls mounted on said shafts, respectively, between the bearings, means securing the ends of said rolls adjacent said second pair of bearings to said shafts but permitting the rolls to shift angularly about axes perpendicular to said shafts adjacent the last mentioned ends, thereby permitting the ends of said rolls adjacent said gear box to move apart, and resilient means disposed between said shafts and their respective rolls for yieldingly retaining said rolls in coaxial relation to said shafts, respectively.

3. A roll of the class described, comprising a hollow cylindrical member, a shaft extending axially through said member, there being clearance between said shaft and the interior of said member, means at one end of said member for mounting the latter substantially coaxially on said shaft and preventing radial movement of said member relative to said shaft but permitting swinging movement of said member relative to said shaft to provide for displacement of the other end of said member radially relative to said shaft, and resilient means disposed between said shaft and

said member at said other end of the latter for normally retaining said roll coaxial with said shaft but yieldable to a radially applied force causing said member to shift out of said coaxial relation.

4. A husking roll comprising a hollow cylindrical member, a shaft extending axially through said member, there being clearance between said shaft and the interior of said member, drive means at one end of said shaft adjacent the end of said member, hub means at the other end of said member for mounting the latter on said shaft and preventing relative shifting movement in a radial direction and also relative rotation therebetween but permitting swinging movement of said member relative to said shaft about a radial axis to provide for generally radial displacement of the drive end of said member relative to the shaft, and resilient means disposed between said shaft and said member adjacent the drive end of said shaft for normally retaining said roll coaxial with said shaft but yieldable to a radially applied force causing said member to shift out of said coaxial relation.

5. A husking roll comprising a hollow cylindrical member, a shaft of square cross section extending axially through said member, there being clearance between said shaft and the interior of said member, drive means at one end of said shaft, hub means at the other end of said cylindrical member engaging said square shaft to transmit driving force therethrough and maintaining that end of said member substantially concentric with said shaft but permitting relative swinging movement about a radial axis to provide for generally radial displacement of the drive end of said member relative to the shaft, and resilient means comprising a plurality of coil springs disposed between said shaft and said member adjacent the movable end of the latter, said springs being disposed on substantially radial axes in opposed relation for normally retaining said roll coaxial with said shaft but yieldable to a radially applied force causing said member to shift out of said coaxial relation.

6. A roll for a harvesting machine, said roll comprising a hollow cylindrical member, a shaft of polygonal cross section disposed within said member and extending axially thereof, drive means connected to one end of said shaft, a plurality of coil springs disposed generally radially and acting in compression between the several sides of said shaft and the inner wall of said member and opposing one another in balanced relation, said springs being positioned adjacent said drive end of said shaft, and hub means having a polygonal socket receiving said shaft for mounting the opposite end of said member on said shaft to transmit drive force thereto and preventing radial displacement of said member relative to said shaft but permitting relative swinging movement between the member and the shaft about a generally radially extending axis at said opposite end of the member.
